his Attorney,

UNITED STATES PATENT OFFICE.

WILLIAM LIVINGSTON DENIO, OF ROCHESTER, NEW YORK.

ELECTRIC SIGNALING AND ALARM APPARATUS.

SPECIFICATION forming part of Letters Patent No. 397,838, dated February 12, 1889.

Application filed December 1, 1887. Serial No. 256,653. (No model.)

To all whom it may concern:

Be it known that I, WILLIAM LIVINGSTON DENIO, a citizen of the United States, residing at Rochester, in the county of Monroe and 5 State of New York, have invented certain new and useful Improvements in Electric Signaling and Alarm Apparatus; and I do hereby declare the following to be a full, clear, and exact description of the invention, such as 10 will enable others skilled in the art to which it appertains to make and use the same.

My invention relates to an automatic fire-alarm in which the melting of a seal fusible at a definite temperature higher than normal will 15 change the connections of an electric circuit, so as to transmit an alarm-signal to some point or station from which preventive measures may most speedily and certainly proceed.

The object of the invention is to produce a 20 fusible seal which, in addition to its capability for use in new plants where any desired arrangement of wiring may be adopted, will be adapted for use in existing systems without alteration of the connections—as, for example, 25 in hotels, where an annunciator is already in use, and it is desirable to have a fire-detective which may be attached to the circuit-closers or push-buttons in the various rooms without difficulty.

30 To these ends my invention consists in a heat-detector adapted to be used in the ordinary push-button in lieu of the "push" commonly used therein, which serves the dual purpose of acting as the push or button and 35 of automatically turning in an alarm on the outbreak of a fire or a definite rise in temperature.

My invention embodies, also, certain features of structure, which will be fully described in the accompanying specification, and definitely indicated in the appended claims.

In the accompanying drawings, which illustrate my invention, Figure 1 is a section of an ordinary circuit-closer. Fig. 2 is a section of 45 such a circuit-closer having the porcelain knob or push removed and my heat-detector inserted in lieu thereof. Fig. 3 is a view in perspective of the parts composing my heat-detector. Fig. 4 is a section of a circuit-breaking push-button having my improvement attached. Fig. 5 is a view in perspective of 50 my detector before application.

In putting my invention into practice I make a barrel, 5, of metal or other suitable resisting material, the integrity of which will not 55 be affected by moderate heat, with an internal flange, 9, near its one end and an external flange, 12, and internal rabbet in said flange at the other end. A spiral spring is placed in the barrel and seated against the flange 9. A 60 pin, 7, is then thrust through the spring. The pin is provided with a head, 11, of sufficient diameter to enter the rabbet in the externally-flanged end of the barrel, and the pin is sufficiently long to project partially or entirely 65 through the orifice in the internal flange, 9, of the barrel. The spring, of course, must be of sufficient length to be under compression when nested in the barrel. When the parts have 70 been assembled, the pin 7 is secured in place by soldering to the barrel and flange, as shown at 8, Figs. 2 and 4. The solder I use for this purpose is one which will fuse at a comparatively low temperature—at 160° Fahrenheit, for instance. By varying its composition it 75 may be made to fuse at a higher or lower temperature, as is well understood in the art. The detector is then completed, and may be supported in position in suitable relation to any pair of circuit-terminals. In Figs. 2 and 4 it 80 is shown mounted in the ordinary push-button. These buttons, as shown in Fig. 1, consist of a base, 1, provided with circuit terminals or electrodes 3 4. Over the base fits a screw-cap, 2, which is provided with a flaring 85 orifice, in which a flanged porcelain knob is placed, the flange of the knob being wider than the orifice and resting on the upper spring-electrode. Such circuit-closers are in use in thousands of existing plants in hotels 90 and other large buildings. By unscrewing the cap 2, removing the porcelain knob, and substituting for it my detector I capacitate such a circuit-closer for giving an alarm on the outbreak of a fire. When the air of any room in 95 which the change has been made reaches a predetermined temperature, the alloy melts and releases the pin 7, which is forced out of the barrel by the expansion of the spring 6. The terminals or electrodes 3 and 4 are thus 100 brought into contact and the alarm transmitted to a central station, where measures can immediately be adopted for extinguishing the fire.

The device is applicable, also, to closed circuits; in which case the flange rests upon the lower spring, as shown in Fig. 4.

The detector may of course be used elsewhere than at a push-button. It may be inserted at any part of an electric circuit, being supported over one of the terminals, so as to force it away from or into engagement with the other terminal, accordingly as the system is closed or open circuit in character.

Having thus described my invention, what I claim, and desire to secure by Letters Patent, is—

1. A button for circuit-changers laterally extended at one end and containing a spring, a finger pressed by said spring, and a fusible seal normally holding the finger against the tension of the spring.

2. A perforated button for push-buttons flanged at one end and containing a spring and a finger pressed by said spring, said finger being held under tension by a fusible seal on the outer face of the button, whereby said button may be substituted for the customary porcelain button and automatically transmit an alarm on a definite rise in temperature.

3. In a fire-alarm or heat-detector, the combination of a barrel internally flanged at one end, a spring seated against said flange, a pin within the barrel engaging the spring, and a

fusible seal for holding said spring under tension, whereby on the outbreak of a fire the seal will melt and the pin will be thrust out of the barrel.

4. The combination, with circuit electrodes, of the barrel 5, provided with flange 9, spring 6, seated in said barrel, said springs when free extending out of the barrel, and pin 7, one end of which engages the free end of the spring, the other end being secured by a fusible seal to the other end of the barrel, whereby on the outbreak of a fire the seal will melt and the pin will be thrust out of the barrel and the circuit will be changed.

5. The combination of the casing, the hollow button movably secured in the casing, a pin in said barrel, a spring held under tension by said pin, a fusible seal for holding the spring, and the electrodes engaged by the button, whereby the device may normally be operated as a push-button and on the outbreak of a fire will automatically turn in an alarm.

In testimony whereof I affix my signature in presence of two witnesses.

WM. LIVINGSTON DENIO.
